[57] CLAIM

The ornamental design for a toaster, as shown and described.

DESCRIPTION

FIG. 1 is a perspective view as seen from the top, front and left side of a toaster showing our new design;

FIG. 2 is an elevational view of the front end thereof;

FIG. 3 is an elevational view of the rear end thereof;

FIG. 4 is a top plan view thereof;

FIG. 5 is a bottom plan view thereof; and,

FIG. 6 is a left side elevational view thereof, the right side elevational view being substantially similar to the left side elevational view except that the right toaster control knob is partially hidden by one of the convex portions of the front housing panel.

The broken lines in FIG. 5 showing underbody parts including a crumb tray are used for illustrative purposes only and form no part of the claimed design.
